(57) **CLAIM**

The ornamental design for a jar-shaped weight, as shown and described.

DESCRIPTION

FIG. 1 is a perspective front view of a jar-shaped weight;

FIG. 2 is a front view thereof;

FIG. 3 is a top view thereof; and,

FIG. 4 is a bottom view thereof.

The broken lines in the drawings are for the purpose of illustrating portions of the article that form no part of the claim.
